HEAT INTERCHANGER

Pietro Maniscalco, Toledo, Ohio

Application March 26, 1935, Serial No. 13,097

6 Claims. (Cl. 257—235)

This invention relates to improvements in a heat interchanger.

One of the main objects of this invention is to provide an improved heat interchanging device, and more particularly a device for heating fluids, such as air, gas and vapor, by utilizing a hot exhaust fluid which is normally wasted, as for example the exhaust gases from an internal combustion engine.

Another object is to provide a heat interchanging device which is especially adapted for use with my compressed air power unit, whereby the moistened and compressed air is highly heated by the otherwise wasted exhaust gases, so as to greatly increase the pressure and working force in the compressed air and likewise the power output produced thereby.

A further object is to provide such a heat interchanging device which not only heats but also preheats and superheats the compressed air by the use of the exhaust gases of the engine, so as to utilize the normally wasted heat energy thereof to the fullest extent.

These and various other objects and advantages will become apparent from the following description, taken in connection with the accompanying drawing, in which the invention is illustrated in its preferred form of construction, it being understood that various other arrangements and forms of construction may be resorted to for carrying out the objects and purposes of this invention.

In the drawing:

Fig. 1 is a horizontal sectional view illustrating this invention in its preferred form of construction.

Figs. 2 and 3 are vertical sectional views taken, respectively, along lines 2—2 and 3—3 of Fig. 1.

In disclosing this invention I have illustrated it in the drawing only in its preferred form of construction, which comprises a main heating chamber 10 having a preliminary heating chamber or preheater 11 extending laterally from one end thereof, and a superheating chamber or superheater 12 extending forwardly from the other end of the main chamber.

The main chamber 10 is preferably box-shaped or tube-shaped, containing a series of baffle plates 13 which extend from the side wall inwardly in spaced and in overlapping relation, to provide a series of compartments 14, so that the exhaust gases are deflected to and fro around the inner ends of said baffle plates and through the series of compartments, from the head end 15 to the rearward end 16 of the main chamber, there-

by alternately expanding and reconcentrating the flow of gases for better extracting the heat therefrom. A jacket or casing 17 is mounted around the main chamber to provide an insulating air chamber 18 around the same.

As indicated in Fig. 2, a series of pipes 20 are curved to and fro around the inner ends of the baffle plates to extend through the successive compartments 14, from one end of the main chamber to the other, being mounted in the head 10 or front wall 15, opening into the interior of the superheating chamber 12.

The preheater 11 includes an inner conduit or tube 21 which extends laterally from the side wall, adjacent one end of the main chamber, and has an outer rearwardly extending elbow 22 discharging the exhaust gases from the main chamber. A casing 23 is mounted in spaced relation around said tube to provide an insulating air chamber 24 around the same, said chamber 24 being in open communication with auxiliary chamber 18, thus more completely preventing heat from the exhaust gases from being dissipated out of the preheating chamber as well as out of the main chamber. A conduit or pipe 25, for conveying compressed air, extends through chamber 24 into tube 21 of the preheater, and is surrounded by said tube which serves as a heating chamber in which the air is heated which passes through said pipe. This pipe 25 is connected through a coupling member 26 to the series of pipes 20, as best indicated in Fig. 2, for conducting the compressed air through the preheater and through the main heating chamber, into the superheater.

The superheater 12 is preferably arranged substantially funnel-shaped having its broad rear portion connected to head 15, and the contracted front end connected to a pipe 27, for conveying the superheated compressed air to a motor or device to be utilized as desired.

This heat interchanger is especially adapted to be used in connection with an internal combustion engine, as indicated by engine 30, and the superheater preferably extends the length of the engine, being connected to the engine casing by bracket attaching means 31, in such a manner as to provide an air chamber 32 therebetween, to avoid excessively heating that side of the engine. A tube 33 extends substantially the length of the superheater, and has branches 34 extending therefrom and connected with the several exhaust ports of the engine; while the rear end of tube 33 is connected to head 15, and through an opening 35 therein communicates with compart-

ments 14 in the main heating chamber, so as to convey the heated exhaust gases from the engine through the superheater and through the successive compartments of the main chamber then 5 through tube 21 and out through its discharge port 22 into the atmosphere.

All parts of the interchanger exposed to the surrounding atmosphere are properly insulated, as indicated by the insulating coats or covering 37, 10 38, and 39 mounted respectively around the superheating and the main and the preheating chambers of the device.

The materials used in constructing these inner compartments of the device possess the highest 15 coefficient of heat conductivity consistent with the strength required to resist the pressure of the highly compressed air. The air and heat travel in counterflow or in opposite directions, and by this arrangement the greatest transfer of heat from 20 the exhaust gases into the compressed air takes place in the superheater, as the air which leaves pipes 20 expands as it enters the larger end of the superheater, there receiving its final and highly 25 expansive heat energy, then being contracted in the narrower end to increase the pressure and speed or rate of flow thereto as it enters tube 27, for application and use thereafter.

By this device the maximum amount of heat is 30 extracted from the exhaust gases, which are then discharged to the atmosphere as a cooled and dead vapor with only sufficient pressure to expel it. Thereby it overcomes most or all of the 35 harmful, dangerous and obnoxious effects, such as noise, bad odor, poison or fire hazards, and no mufflers or silencers are required.

I claim:

1. A heat interchanger including a superheating chamber and means for connecting it to an engine, a preheating chamber and a main 40 chamber operatively connecting it with the superheating chamber, conduit means for conducting the compressed air through the preheating and main heating chambers into the superheating chamber, conduit means extending through the 45 superheating chamber and having branch means extending to the engine for conducting the hot exhaust gases from the engine through the superheating chamber wherefrom it flows through the main and preheating chambers, in counterflow 50 over the compressed air conduit therein, and means for providing an insulating air chamber around the main chamber.

2. A heat interchanger and means for connecting it to an internal combustion engine, said interchanger comprising a main chamber including 55 a series of baffle plates which are spaced and overlapping at their inner edges to deflect gases to and fro through said chamber, a superheating chamber on the main chamber and being connected to the engine, a conduit extending through the superheating chamber to the main chamber and having branch conduits for conducting exhaust 60 gases from the engine, and conduit means curved around the inner ends of the baffle plates for conducting air through the main chamber to the superheating chamber in counterflow to the flow of gases, thereby heating to a high degree the compressed air flowing through the device.

3. A heat interchanger comprising a main 65 chamber and a funnel-shaped superheating chamber having its larger end connected to one end thereof, means for connecting the superheat-

ing chamber to an engine, conduit means extending the length of the superheating chamber to empty into the main chamber and having branch conduits thereon for conducting exhaust gases from the engine, and conduit means extending through said main chamber for conducting air therethrough to flow into and expand and be superheated in the superheating chamber in counterflow to the flow of gases. 5

4. A heat interchanger adapted for use in conjunction with an internal combustion engine and with compressed air conducting means, said interchanger comprising a main chamber having a series of baffle plates extending from the side wall inwardly in spaced and overlapping relation at 15 their inner ends to deflect gases to and fro therethrough, there being a preheating chamber at one end and a funnel-shaped superheating chamber at the other end with the larger part thereof connected to the head of said end, means for connecting the superheating chamber to the engine to provide an air chamber between the two, an air conduit extending through the preheater, a plurality of curved conduit means extending to and fro along the said baffle plates from the rear wall 25 to the front wall of the main chamber, said means being connected to said air conduit, an exhaust tube in the superheating chamber adapted to discharge into the main chamber and having branch tubes receiving the hot exhaust gases from the 30 engine, whereby the exhaust gases pass in counterflow over the air conveying means through the main and the preheating chambers, and casing means providing an insulating air chamber around the main and the preheating chambers. 35

5. A heat interchanger for connection with an internal combustion engine comprising a main heat interchanging portion having a super-heater thereon, bracket attaching means for connecting the super-heater to the internal combustion engine in spaced relation thereto to provide an insulating air space therebetween to avoid excessive heating of the engine, means for conducting air through said main portion to the superheater, and conduit means in the super-heater to be connected with the exhaust means of the engine for conducting exhaust gases from the engine through said super-heater to the main portion, in heat interchanging relation and in counterflow to the flow of said air through the device. 40

6. A heat interchanger adapted for use with an internal combustion engine, comprising a main chamber having overlapping members therein also having a preheating chamber adjacent one end and a superheating chamber at the other, 55 bracket attaching means for connecting the superheater to the internal combustion engine in spaced relation thereto to provide an insulating air space therebetween to avoid excessive heating of the engine, means for conducting compressed air through the preheating and the main chambers to the superheating chamber, and conduit means connected with the engine and extending through the superheating chamber for conducting the hot exhaust gases from the engine 60 through the superheating chamber to the main chamber to pass to and fro around said overlapping members and into the preheating chamber, in counterflow to the flow of air through the device, to utilize the heat energy of the exhaust 65 gases to a maximum extent. 70

PIETRO MANISCALCO.
